UNITED STATES PATENT OFFICE

1,995,967

COVER FOR COLLAPSIBLE TUBES

Roger Lucien Demers, St. Jaques, New Brunswick, Canada, assignor of one-half to Martin Therriault, Edmundston, Canada

Application March 27, 1934, Serial No. 717,625

2 Claims. (Cl. 221—60)

The object of this invention is to provide an improved cover for a collapsible tube.

A further object of the invention is to make the cover a slidable one convenient and easy to operate.

5 A still further very important object of the invention resides in the provision of a cover for collapsible tubes which is exceedingly simple in its construction, inexpensive to manufacture, sufficient, durable, thoroughly reliable in use and 10 otherwise well adapted to the purpose for which it is designed.

With the above and numerous other objects in view as will appear as the description proceeds, the invention consists in certain novel features 15 of construction, and in the combination and arrangement of parts as will hereinafter be more fully described and claimed.

In the drawings:

Figure 1 is a fragmentary side elevation showing 20 the upper end of a collapsible tube having a cover embodying the features of my invention.

Figure 2 is a similar view taken at right angles to that shown in Figure 1.

Figure 3 is a sectional view taken substantially 25 on the line 3—3 of Figure 2.

Figure 4 is a sectional view taken substantially one the line 4—4 of Figure 1.

Figure 5 is a top plan view of the tube, and

Figure 6 is a perspective view showing the cover 30 disassembled.

Referring to the drawings in detail it will be seen that the numeral 5 denotes a collapsible tube having formed thereon a parallelopipedal block-like neck 6 having a rectangular opening 7 extending through a portion thereof adjacent one end and having rising from the corners thereof tabs 8 which are bent to overlie the top surface of the neck 6. Numeral 9 denotes a rectangular plate slidable on the upper surface of the neck 6 and having a rectangular opening 10 which may be brought into registry with the opening 7. Stop lips 11 depend from the ends of the plate 9. With the plate in the position shown in Figure 3 it will be noted that the opening is closed and by sliding the plate to the dotted line position shown in Figure 3 it will be noted that the passage is in open position.

It is thought that the construction, simplicity and advantages of this invention will now be 50 quite apparent without a more detailed description thereof.

The present embodiment of the invention has been described in considerable detail merely for the purposes of exemplification since in actual 55 practice it attains the features of advantage

enumerated as desirable in the statement of the invention and the above description.

It will be apparent that changes in the details of construction, and in the combination and arrangement of parts may be resorted to without departing from the spirit or scope of the invention as hereinafter claimed or sacrificing any of its advantages.

Having thus described my invention, what I claim as new is:

1. A discharge neck for a collapsible tube, said neck comprising a relatively heavy solid block having a flat top provided with a plain rectangular surface, said top having relatively heavy solid inverted L-shaped portions rising therefrom at 15 the corners of said rectangular surface and having their foot-portions spacedly overlying said surface, and a relatively thick plate having a parallel sided portion of uniform cross section lying between said L-shaped portions and slidably engaged with said rectangular surface and the inner sides of said foot-portions and the inner sides of the standard-portions of said L-shaped portions, the opposite ends of said plate having depending parts engageable with the opposite ends 20 of said block to limit sliding movement of said plate, said plate and said block being formed with registrable openings.

2. As a new article of manufacture, a neck for a collapsible tube, said neck comprising a generally rectangular heavy solid block formed with an opening therethrough and a plain flat top through which said opening opens, opposite ends of said top being formed with a pair of heavy solid inverted L-shaped bodies of generally rectangular cross section and rising from said top so that the outer sides thereof are vertically aligned with the corresponding outer sides of said block and one edge thereof is vertically aligned with the adjacent end of said block, the opposite edges of said L-shaped bodies at the same side of said block being considerably spaced from each other, and a closure in the form of a heavy solid plate formed with an opening registrable with said opening in the block, said plate having a flat body and plain side edges slidably engaged with said top and with the inner sides of the standard portions of said L-shaped bodies, respectively, side portions of the upper surface of said plate being slidably engaged with the undersurfaces of the foot-portions of said L-shaped bodies, and depending stops on the opposite ends of said plate engageable with the ends of said block to limit the opening and closing of said closure.

ROGER LUCIEN DEMERS. 55
